wick, England

Application May 7, 1947, Serial No. 746,516
In Great Britain February 19, 1947

2 Claims. (Cl. 188—79.5)

1

This invention has reference to improvements relating to brakes and is concerned with brakes in which there is interposed between the surface on which the braking effort is to be exerted and an abutment means, a stop means which co-operates with the abutment means for determining the "off" position of the means for applying the braking effort and which is associated frictionally with the said applying means in such a manner that the stop means aforesaid moves with the applying means both during the application of and upon the relieving of the braking pressure, but, as braking operations are performed, is capable of being displaced automatically relatively to the applying means as wear of the applying means takes place by an amount commensurate with the degree of such wear so that the stop means and abutment means co-operate to arrest the movement of the applying means to the off position whenever a substantially predetermined clearance obtains between the applying means and the surface to be braked.

With brakes as aforesaid it has been experienced that where withdrawal of the applying means is effected by strong "pull off" springs it is necessary to impose such a high frictional loading between the stop means and the brake applying means that the stop means is prone to squeak and wear when it contacts the braking surface and also to mark the said surface and furthermore after wear of the braking surfaces has taken place upon a subsequent application of the brakes there is a tendency for the drag induced on the brake applying means as the braking pressure is applied to displace the stop means so that in some constructions it may not contact the fixed abutment means when the braking pressure is relieved.

The present invention has for its object to provide an improved and simplified means which ensures a high frictional resistance between the stop means and the brake applying means when the said applying means is in the "off" position and only sufficient frictional resistance to ensure that the stop means moves with the said applying means whenever the stop means is out of contact with the abutment means but without preventing displacement of the stop means in either direction relatively to the applying means if such movement is required and provided of course that the displacing force is sufficient to overcome the aforesaid frictional resistance.

According to the invention an improved brake as aforesaid is characterised in that the stop means is mounted on a brake applying means so as to be capable of displacement in either direc-

2

tion against frictional resistance whenever the stop means is out of contact with the abutment means and in that when the stop means is in contact with the abutment means forces are set up which cause a binding between the stop means and its mounting on a brake applying means so bringing into play automatically a high frictional resistance between the stop means and its mounting whenever the stop means is in contact with the abutment means which ensures that movement of the applying means to the "off" position is arrested when a predetermined clearance between the applying means and the surface to be braked is attained.

15 The invention will now be described with particular reference to the accompanying drawings wherein:

Figure 1 is a view partly in section and partly in elevation illustrating somewhat diagrammatically the invention as applied to an hydraulically actuated two shoe internally expanding brake for motor vehicles, which in general is of known construction.

Figure 2 is a fragmentary view on an enlarged scale showing in plan but partly sectioned, the stop means and mounting incorporated in Figure 1, and

Figure 3 is a fragmentary view partly in section and also on an enlarged scale showing the manner 30 of mounting the stop means utilised in the construction illustrated in Figures 1 and 2, the section being taken on the plane indicated by the line 3—3 Figure 2 looking in the direction of the arrows to said line.

35 The brake as depicted in the drawings incorporates two similar brake shoes 4a, 4b the lower ends of which abut a fulcrum about a pivot pin 5 fixed to the back plate 6. The upper ends of the brake shoes 4a, 4b abut the ends of plungers 7a 40 which are associated with oppositely acting pistons 7 mounted in an hydraulic cylinder 8 to which hydraulic pressure is applied by way of an inlet port 8a in the normal manner. The pistons 7 are provided with the usual hydraulic packings 9 and co-operate with a spring 10 interposed between the pistons which tends to force the pistons 7 apart.

45 The brake shoes 4a, 4b have fixed to the periphery thereof linings 12 of material having a high co-efficient of friction.

50 The web of the brake shoe 4a, which shoe serves as a leading shoe during forward travel, has secured thereto a pin 13 having an intermediate elongated portion 13a which is of a rectangular shape in cross section.

This elongated portion 13a is mounted within an elongated slot 14a formed in the arm 14b of a stop member 14 of substantially inverted L shape and the said elongated portion 13a is of slightly lesser depth than the depth of the slot 14a.

Interposed between a washer 15 in abutment with the arm 14b and a washer 16 secured on the outer end of the pin 13 is a coil spring 17, said spring 17 causing the arm 14b to be gripped between the said washer 16 and a cylindrical enlarged portion 13b arranged on the opposite side of the web to the washer 15 so that a frictional resistance to axial displacement of the arm 14b is imposed by the pressure exerted by the washer 15 on the marginal portions bounding the slot 14a.

The pin 13 is also provided with a threaded portion which is engaged by a nut 18 so that the pin 13 may be secured to the web of the shoe 4a by clamping the said web between the enlarged portion 13b and the nut 18.

The outer end of the arm 14b has secured thereto a separately formed plunger portion 14c which passes through a hole in the table of the shoe 4a and through a hole in the frictional lining 12 associated therewith.

The depending limb 14d of the stop member 14 is adapted to abut the inwardly directed tapered portion 19a of a pin 19 having a screw threaded portion mounted in a screw box 6a associated with the back plate 6, said pin 19 also having an externally squared portion 19b for the reception of a tool whereby the said taper pin 19 can be adjusted relatively to the back plate 6 as required.

The tapered pin 19 is adjusted initially so that when the arm 14d is in contact therewith the distance between the centre of the elongated portion 13a and the outer end of the plunger portion 14c is less than the distance between the centre of the elongated portion and the surface to be braked by an amount corresponding to the clearance required to be maintained between the applying means and the surface to be braked when the applying means is in the "off" position. The distance between the centre of the projecting portion 13a and the outer end of the plunger 14c defines the effective length of the arm 14b.

Thus subject to the light frictional resistance to displacement imposed by the spring loaded washer 15 the stop member 14 is displaceable toward and away from the drum 20 whenever the depending limb 14d is out of contact with the tapered abutment portion 19a of the pin 19 but whenever the brake shoes 4a, 4b are retracted by the "pull off" spring 11 the thrust exerted between the lower end of the depending limb 14d of the stop member 14 and the abutment pin 19 gives rise to a couple acting at the ends of the elongated portion 13a. As a consequence whenever the depending limb 14d of the stop member 14 is in contact with the tapered abutment portion 19a of the pin 19 the forces induced effect a canting of the limb 14b of the stop member 14 relatively to the elongated portion 13a of the pin 13, see Figure 3 which occasions a binding between the said elongated portion 13a and the top and bottom walls of the slot 14a which is sufficient to prevent displacement of the stop member relatively to the brake shoe 4a despite the effort of the "pull off" spring 11.

Preferably the ratio in length of the distance

between the point of contact between the tapered portion 19a and the depending limb 14d of the stop member 14 and the pin 13 and between the said pin 13 and the place where the plunger 14c projects through the table of the brake shoe 4a is in the order of 3 or 4—1.

The frictional resistance imposed by the spring loaded washer 15 is provided in order to ensure that the stop member 14 shall move with the brake shoe 4a whenever the said stop member 14 is out of abutment with the tapered portion 19a and is only required to be just sufficient for this purpose.

An automatic adjustment means according to 15 the invention is not prone to squeaking due to contact between the stop member 14 and the brake drum 20 and wear due to contact between the brake drum 20 and the stop member 14 is minimized since on the application of a brake 20 subsequent to wear of the braking surfaces the drag exerted on the then projecting end of the plunger 14c effects a canting of the stop member 14 relatively to the elongated portion 13a of the pin 13 whereby the axis of the elongated slot 14a tends to approach coincidence with the axis of the elongated portion 13a so that inward displacement of the stop member 14 is permitted and so that when the brakes are subsequently returned to the "off" position and the stop member 14 locked by contact with the tapered portion 19a the predetermined clearance between the frictional linings 12 and the brake drum 20 is maintained.

35 We claim:

1. An automatic brake adjustor for an internal expanding brake having a cylindrical drum, a partially cylindrical shoe located interiorly of the drum and pivotal relative thereto into and out of engagement therewith, means for forcing the shoe outwardly into engagement and resilient return means, the automatic adjustor comprising, in combination, an abutment mounted on an immovable portion of the brake, a pin 40 mounted on said shoe and having a radially and axially extending flattened portion, an adjustable stop member mounted for cooperation between said pin and said abutment to position said shoe when in disengaged position, said stop member 45 having two angularly extending arms, one of said arms having a longitudinally extending, parallel-sided slot cut therein, the member being positioned over said pin with said flattened portion extending loosely through the slot in said member, there being a slot through the cylindrical face of said shoe, the end of the slotted arm of said member extending through the slot in said shoe and being engageable with the inner surface of said drum when said shoe is engaged 50 therewith, the slot in the arm of said member having two angularly extending arms, one of said arms having a longitudinally extending, parallel-sided slot cut therein, the member being positioned over said pin with said flattened portion extending loosely through the slot in said member, there being a slot through the cylindrical face of said shoe, the end of the slotted arm of said member extending through the slot in said shoe and being engageable with the inner surface of said drum when said shoe is engaged 55 therewith, the slot in the arm of said member being longer radially than the flattened portion of said pin, the other arm of said member engaging said abutment when said shoe is in disengaged position, and resilient means for holding 60 said member on said pin.

2. An automatic adjustor according to claim 1 in which the stop member is a flat, bell-crank shaped lever with its faces lying in a vertical plane extending substantially perpendicularly to the axis of the brake drum, the slotted arm extending generally radially of the brake and the abutment engaging arm extending at an angle thereto whereby engagement between the abutment and the engaging arm pivots said stop member relative to said pin, engaging the edges of

the flattened portion thereof with the walls of the slot in the arm of said stop member and preventing translation of said stop member radially of said brake relative to said shoe.
